UNITED STATES PATENT OFFICE.

PAUL H. MILLER, OF BALTIMORE, MARYLAND.

SHAVING SET.

Application filed December 5, 1923. Serial No. 678,693.

To all whom it may concern:

Be it known that I, PAUL H. MILLER, a citizen of the United States, residing at Baltimore, in the county of Baltimore and State of Maryland, have invented certain new and useful Improvements in Shaving Sets, of which the following is a specification.

This invention relates to improvements in shaving sets and particularly that type which is especially adapted for travelers' use.

An important object of my invention is to provide a shaving set which combines the brush, soap, safety razor and blades in a compact container.

A further object of the invention is to provide a shaving set whereby the brush may be inverted, when not in use and carried within the container.

A further object of the invention is to provide a device of this character which is durable, inexpensive, and efficient for the purpose intended.

Other objects and advantages of this invention will be apparent during the course of the following description.

In the accompanying drawings forming a part of this specification and in which like numerals are employed to designate like parts throughout the same:

Figure 1 is a top plan view of the device in the closed position,

Figure 2 is a side elevation of the same,

Figure 3 is a horizontal section taken on the line 3—3 of Figure 2,

Figure 4 is a vertical sectional view taken on the line 4—4 of Figure 1,

Figure 5 illustrates the device with the brush in operative position and the container partly open.

Figure 6 is a horizontal sectional view taken on the line 6—6 of Figure 5, and

Figure 7 is a detailed view of the soap and retaining member.

In the drawings, wherein for the purpose of illustration is shown the preferred embodiment of my invention, the numeral 10 generally denotes the body of the container which is preferably metallic although other material may be employed, if desired, and is hexagonal in form. The upper portion of the container is substantially conical in form as at 11, one half of said conical extension being free to swing about a hinge 12 which is suitably secured to the container.

Triangular openings 13 are formed in the upper portion of the container to permit air to gain access therein. A collar formed of semi-circular bands 14 and 15 is secured to the upper portion of the container, the collar 15 having angular projections formed at its extremities for engaging a pin 16 which is carried by a brush. As it is desirable to separate the upper portion of the container from the lower, I have provided a horizontal partition 17, said partition having a tubular compartment 18 secured thereto.

The bottom of the container is enclosed by a disk 19 which has an externally threaded collar 20 secured thereto and adapted to engage suitable threads formed on the lower portion of the tubular compartment 18. The threaded collar 20 also serves as retaining means for the soap 21, which is cylindrical in shape and commonly employed for this purpose. A plurality of vertical partitions 22 are employed to strengthen the device and divide the container into side compartments 23 which may be utilized for the purpose of storing blades 24 and other paraphernalia.

A shaving brush generally denoted by the numeral 25 has a cylindrical shank 26 preferably constructed of rubber in order to firmly retain the bristles 27, and a semi-spherical cap 28 adapted to slightly overlap the shank 26 and engage the bands 14 and 15.

In use, to open the container and invert the brush member in order to apply lather to the face, the collar 15 is disengaged from the pin 16 and the upper hinged section swung outwardly, the brush being then inverted and the hinged section once more returned to the closed position, thereby securely retaining the brush ready for operation. The bottom disk 20 is then disengaged from the container and the soap made ready for use.

After the user has completed the shaving operation, the soap is once more inserted within this compartment and the brush inverted and secured within the container, where it may thoroughly dry out by means of air circulating through the openings 13.

It is to be understood that the form of my invention herewith shown and described is to be taken as the preferred example of the same, and that various changes in the shape, size, and arrangement of parts may be resorted to, without departing from the spirit

of the invention, or the scope of the subjoined claims.

Having thus described my invention, I claim:

- 5 1. A device of the character described comprising a hexagon-shaped container, the upper portion of the container being tapered and having a plurality of openings therein, the lower portion of the container being divided into a plurality of compartments, one-half of the upper portion of the container being hingedly connected to the lower portion, a pair of semi-circular bands secured to the upper portion of the container, a shaving brush which is held in upward or downward position by means of the semi-circular bands, a disk having a threaded collar formed thereon, a bar of soap within said threaded collar, and means for connecting the disk and threaded collar to the container.
- 10 2. A device of the character described comprising a hexagon-shaped container, the upper portion of the container being tapered and having a plurality of triangular openings therein, one-half of said upper portion being hingedly connected to the lower portion of the container, a horizontal partition formed within the container separating the upper and lower portions thereof, a tubular partition formed in the central portion of the container, the lower portion of said tubular partition having screw threads formed therein, a plurality of vertical partitions forming a plurality of compartments in the container, a pair of semi-circular bands secured to the upper portion of the container said bands having apertures formed near the extremities thereof, a shaving brush, a pin secured to the shank of said shaving brush, the pin being adapted to engage the openings formed in the bands and retain the

brush in an upward or downward position, a disk, a threaded collar formed on the upper portion of the disk, the threaded collar adapted to retain the soap therein, and the threaded collar also being adapted to engage the threads on the lower portion of the tubular compartment and retain the disk on the lower portion of the container.

45 3. A device of the character described comprising a hexagonal container, the upper portion of the container being tapered inwardly and having a plurality of openings therein, one-half of the upper portion of the container being hingedly connected to the lower portion, a hinge for securing the upper portion to the lower portion of the container, a pair of semi-circular bands having apertures through their extremities secured to the upper portion of the container, a shaving brush, a pin carried by said brush adapted to engage in the apertures in said circular bands, a horizontal partition formed in the container to 55 separate same into upper and lower portions, a tubular vertical partition formed in the center of the lower portion of the container, a plurality of vertical partitions formed in the lower portion of the container and dividing same into a plurality of compartments, a circular plate, a threaded collar formed on the upper portion of the circular plate, means whereby a bar of shaving soap may be retained in the threaded 60 collar, and means for connecting the circular plate to the bottom of the container.

50 In testimony whereof, I have affixed my signature in the presence of two witnesses.

PAUL H. MILLER.
